(57) **CLAIM**

The ornamental design for a plastic container, as shown and described.

DESCRIPTION

FIG. 1 is a perspective view of the container showing our new design and showing the top, front and left side thereof;
FIG. 2 is a left side elevation view thereof;
FIG. 3 is a front elevation view thereof;
FIG. 4 is a rear elevation view thereof;
FIG. 5 is a bottom plan view thereof; and,
FIG. 6 is a top plan view thereof.

The broken lines shown in the drawing disclosure are for illustrative purposes only and form no part of the claimed design.
